FOLDABLE BRUSH

Harold Fredrickson, Minneapolis, Minn., assignor to Lactona Incorporated, Ramsey, Minn., a corporation of Minnesota

Application September 28, 1956, Serial No. 43,141

Term of patent 14 years

(Cl. D9—2)

FIG. 1

Figure 1 is a perspective view of a foldable brush in closed position, showing my new design;

I claim:

The ornamental design for a foldable brush, substantially as shown and described.
